UNITED STATES PATENT OFFICE.

STEPHEN TAFT, OF WORCESTER COUNTY, MASSACHUSETTS.

CUTTING-NIPPERS.

SPECIFICATION forming part of Letters Patent No. 351,478, dated October 26, 1886.

Application filed June 30, 1886. Serial No. 206,708. (No model.)

To all whom it may concern:

Be it known that I, STEPHEN TAFT, a resident of the county of Worcester, in the State of Massachusetts, have invented Improved 5 Cutting-Nippers, of which the following is a specification.

My improvement relates, mainly, to such nippers as have their cutting-edges at right angles, or nearly so, to their handles, and whose 10 edges pass each other as they cut, though they may be applied wholly or in part to others. It is designed to enable them to do more work 15 with the same power, or the same work with much less power, than any made in the common way. This is accomplished by causing the cutting-edges to approach each other at an angle instead of parallel to each other, one or both edges being made at an angle varying from a right angle to their line of motion, at which 20 angle such nippers have hitherto been made, so that in cutting anything like a wide piece or a coil of wire they cut progressively and successively in a flat piece cutting one edge first and across progressively to the other, and 25 in the coil cutting one wire off first and the others successively. This successive shear-cut is made by giving the cutting-edges an angular or diamond form from some point, preferably the middle part, though for some purposes it may be placed at one side. Thus the 30 edges will approach each other angularly and not parallel, but more or less differing from a right angle to their line of motion, and also holding or supporting the loose end by means 35 of a rest near by holding it from being bent over the edge in cutting, so that a much thicker or harder piece may be cut than if not so held. This is accomplished by extending the fulcrum-pin, or a portion of it, to make a rest on 40 that side of the edges, the other being usually held, and also by making a groove or grooves in one or both of the edges, so that in cutting a coil of wire the cutters shall overlap one or more turns, as desired, without cutting, and 45 cut beyond them, forming rings of two, three, or more turns of the wire, and by using several grooves a corresponding number of rings may be cut at one stroke, a notch being made in the side of the jaw, if necessary, to give room 50 for inserting the coiled wire. These features of my improved cutting-nippers make it a com-

plete tool for a great variety of work, and when used by any kind of power or by hand requiring much less force to do the work than others.

In the accompanying drawings illustrating 55 a pair of nippers embodying my invention, Figure 1 is a side view. Fig. 2 is a front view of the jaws as seen from the left of Fig. 1, and Fig. 3 shows some cuts illustrating its work. 60 Fig. 4 is a perspective view of the head of the nippers, showing clearly the cutting-edges and the notches in the edge on one side.

The same letters indicate the same parts 65 wherever they occur.

A A are the handles, made in most any of the usual forms, and having a strong joint at the fulcrum-pin B. This pin B, or a part of it, is extended on each side to form a rest for the end of the work, being cut off, as at d', 70 Fig. 1.

C C are the jaws, preferably made with thick lips passing each other, and with their edges in the diamond or angular form shown in Fig. 2, so that a small part only is cutting at any 75 time. The jaws C C have also notches G G, made to allow a coil of wire to pass over between the edges, which have one or more grooves, c c', made in one or both, with cutting-edges left between large enough to cut one 80 wire of the coil, the spaces being made for the purpose of leaving one, two, or more turns of the wire uncut, thus forming rings of two, three, or more turns, as at e e', Fig. 4, several 85 grooves cutting a corresponding number of rings from a coil, E, at one stroke. At D, Fig. 3, is shown a wide piece partly cut, showing the progressive cut, the lines b b and b' b' indicating the position of the cutting-edges.

I am aware that it is not broadly new to 90 have cutting-jaws at right angles to the handles, nor to have grooves in the edge of rod-cutters, nor to make shear-cutting edges in metal-cutting tools.

Having thus fully described my invention, 95 what I claim therein as new, and desire to patent, is—

1. In cutting-nippers, the jaws C C, at right angles to the handles, each jaw having a cutting-edge in diamond or angular form, whereby on either side a progressive or shear cut 100 can be made, substantially as described.

2. In cutting-nippers, in combination with the jaws C C, at right angles to the handles, each jaw having cutting-edges in angular form, the fulcrum-pin B, extended and forming a rest for end of the work.
3. In cutting-nippers having an extended fulcrum-pin, one jaw having an angular cutting-edge and the other provided with alternate grooves and angular cutting-edges, substantially as described.
4. The jaws C C at right angles with the handles, each having diamond-shaped cutting-edges, as described, and one provided with grooves in one edge and having a notch, 15 G, whereby the wire coil can be suitably adapt-

ed to the notched cutting-edges to be cut at any point desired.

5. As an article of manufacture, the cutting-nippers herein described, consisting of a pair of cutting-jaws pivoted together by a fulcrum-pin which extends on each side, said jaws being at right angles with the handle and each notched in the side and having diamond or angular cutting-edges, the cutting-edge of one jaw notched, substantially as shown and described. 20 25

STEPHEN TAFT.
